UNITED STATES PATENT OFFICE.

JOSEPH ARMSTRONG, OF ALLSTON, MASSACHUSETTS, ASSIGNOR TO AMERICAN MOISTENING COMPANY, OF BOSTON, MASSACHUSETTS, A CORPORATION OF MAINE.

HUMIDIFIER.

Application filed October 8, 1928. Serial No. 140,373.

This invention relates to improvements in humidifiers. More particularly it relates to a lint and dirt collector adapted to be set in the drip-pan of a humidifier, especially one of the vertical forced draft type, whereby lint and other foreign matter, which may find its way into the drip-pan, will accumulate on the collector in such manner as not to interfere with the free flow of water from the pan into the waste or return pipe thereof.

Humidifiers of this type, having open inflow from the room air, are at all times receptive to fibres of lint and other foreign matter floating in the room air. In factories where fibrous materials are in process of manufacture, the amount of this floating foreign matter often is considerable. Its tendency to accumulate in the drip-pan of the humidifier necessitates annoyingly frequent inspections and cleanings of the screen covering the outlet, where a relatively small clogging accumulation may cause the overflow or the blowing of water from the pan, with consequent injury to materials in the room.

It is among the objects of the present invention to provide effectually against this clogging of the waste or return pipe, by inserting in the drip-pan a lint and dirt collector which will permit free flow of water from the drip-pan even after a considerable quantity of foreign matter has accumulated upon it; also to reduce the maintenance cost of such humidifiers by greatly reducing in number and frequency the inspections and cleanings necessary to insure proper humidifier operation. Still another object is to provide for simple, quick and efficient removal of accumulated lint. It is moreover, an important feature that the device as a whole readily may be incorporated in humidifiers already built, of types as now commonly constructed.

These objects are attained by setting a forest of upstanding lint collecting pins in positions distributed over the pan bottom, around the central drainage opening. Water flowing shallowly among them is strained of its lint, which is arrested and held by the pins. The pins may be set in circular rows, both the rows and the pins being at comfortable distances apart, so that a relatively large amount of foreign matter may collect

on each pin, without obstruction of the passages available for water to flow to the outlet. 55

The said bottom holding the pins may be a false bottom, comprising a thin disk set horizontally and loosely over the regular or tight bottom of the pan. 60

Quick and efficient removal of accumulated lint and dirt is provided for by another feature of the invention, by which an overlying, thin and perforated removable disk serves as a removable top surface of the first disk, and when removed is free from all entangling pins, but still holds the lint. This second disk may have a central opening with depending spout which can be set down through the pin-disk into the waste pipe, to guide the water thereinto and to center both disks in the pan. The water flows over this top disk and all lint which collects about the pins lies upon this. When this disk is lifted from the pin-plate the foreign matter which has collected about the pins is stripped from them all simultaneously and is removed with the cleaning plate as on a tray; whence it can be wiped clean with the entire cleaning operation having consumed only a fraction of a minute. 80

It is intended that the patent shall cover by suitable expression in the appended claims whatever features of patentable novelty exist in the invention disclosed. 85

In the accompanying drawings:

Figure 1 is an elevation of a humidifier embodying the present invention with the left half of the casings in medial section;

Figure 2 is a plan of the collector bottom, shown as a removable disk; and 90

Figure 3 is a perspective view of its cleaning plate.

Referring to the drawings, and more particularly to Figure 1, a well known type of humidifier having interior vertical air current is seen, adapted to be hung from overhead by a pair of hanger straps 10 between which is attached a spider 12 supporting the motor 14 and fan 16. The upper section 18, of open-ended tubular casing, has the fan disposed therein so as to drive air downward; and an inward projecting flange 20 on this casing, close above the fan, frustrates any tendency of the air to flow backward when thrown laterally off the tips of 95

100

105

the blades. A second inward projecting flange 22 on casing 18 below the fan, concentrates the air blast discharged from casing 18 for entrance to the lower section 24 of tubular casing. This latter section of casing is spaced a little below the upper section, and other air is drawn into the lower casing 24 by the injector effect of the draft of air passing from the upper to the lower casing.

The usual nozzle 26 makes a conical spray downward toward the walls of the casing, from which the passing air entrains moisture before passing out horizontally in all directions. The deflector 28 is spaced slightly from the bottom of the drip-pan 32 to permit waste water from above to flow to the outlet and escape into the waste or return pipe 34.

Without the present invention floating lint makes trouble by accumulating in the drip-pan 30, and clogging its outlet to the waste pipe 34. A small accumulation of it there may cause water to rise in the pan.

According to the invention this foreign matter is to be collected and held before it reaches the outlet so as not to interfere with the flow of water from the drip-pan. In the bottom of the pan, or, as illustrated, in a false bottom consisting of a thin plane disc or pin-plate 36, inserted underneath the deflector 28, are distributed the multiplicity of pins 40 which do this. The pin-plate 36 rests upon the pan bottom with its periphery in close engagement therewith, so that all water flowing to the waste pipe 34 must pass over the pin plate. A central discharge opening 38 in the pin-plate registers with the entrance to the drain pipe. Arranged in circular rows or otherwise as may be convenient around the central opening 38 a multiplicity of pins 40 each preferably somewhat tapering, extend upward high enough to rise above any water flow that is ever likely to pass over this plate. The pins in each row and the rows themselves are spaced apart so as to allow free flow of water around the pins, but not so much as to permit lint and other foreign matter to pass. Those nearer to the central opening 38 may be set closer together; and all may be so arranged with respect to each other that the water must take a zig-zag route as it passes to the outlet. In so passing, lint and dirt is arrested by the pins. The action is particularly certain because the large area of the plate and its horizontal position makes the water spread out thin upon it and flow slowly, so that lint is easily caught. If by chance any of the water should escape under the plate 36 it will be rid of foreign matter because of the extreme thinness of the place through which it has thus passed. Because of the number, height and arrangement of the pins 40, a large amount of foreign mat-

ter may be collected upon them without the way of the water being obstructed, for water can flow up over any accumulation, and lint and dirt can still be taken from it until the pins are loaded to their total height. The minimum time within which such a loaded condition possibly can arise will be far longer than with any of the devices heretofore advanced, so far as known to me.

The lint or other material can be cleared away at convenient seasons by any suitable method, but for quick and efficient removal of the accumulations the invention comprises also a cleaning plate 42. This comprises a thin plane disk adapted to rest closely on the first. It has small holes 44 equal in number and position to the pins on the pin plate, each hole a trifle larger than the largest diameter of its pin, so that it is easily removable and replaceable. A central opening in this cleaning plate has a depending spout adapted to extend down through the central opening 38 in the pin plate and fit into the entrance to waste pipe 34. The cleaning plate is thus positioned to lie flat upon the pin plate with the pins of the latter projecting up through the holes 44 during operation; but it plays no part in the normal straining function of the device. To clean the apparatus, however, after the humidifier parts above it are moved out of the way, a handle 48 facilitates the lifting of the cleaning plate out of the pan while leaving the pin plate therein. As the cleaning plate is raised the pins 40 are stripped clean; the pins themselves disappear from the cleaning plate, so that it presents a smooth top surface holding the lint; and the lint thereon can be easily and quickly wiped off.

I claim as my invention:

1. The combination, with a pan and drain, of a lint collector comprising a horizontal plate set in the pan in the course of water therein flowing to the drain, with a multiplicity of arresting elements on the plate and distributed through said course.

2. The combination, with a pan and drain, the pan being circular with drain at its centre, of a lint collector set in the pan, comprising a thin disc forming a false bottom for the pan, with central opening in register with the inlet of said drain, and with a multiplicity of upstanding pins spaced apart slightly and set in a group around said opening and in the path of the water as it flows to the said drain.

3. The combination, with a pan and drain, of a separator for foreign material comprising a multiplicity of arresting elements distributed in the bottom of said pan, in the path of flow of water to said drain, and a removable cleaning plate adapted to lie in said bottom under the said flow of water and with said arresting elements rising through

the water above it; said plate cooperating with said elements to strip them of accumulated material when said plate is lifted from them.

5 4. The combination, with a pan and drain, of means to arrest solid material flowing with the water while permitting passage of the water to the drain; and removable means, normally underlying the arresting means, 10 adapted when removed to take from said arresting means its accumulation of arrested material.

5 5. A separator for fibres in water comprising a plate having a multiplicity of pins 15 upstanding from its surface and distributed over a part of the plate over which the water flows, the said pins being arranged in staggered relation to each other and to the direction of flow of water past them, com-

bined with a cleaning plate for said pins, 20 adapted to lie on said pin plate as a separable top surface thereof, having holes registering with and fitting the pins.

6. The combination, with a pan and drain, 25 of a disc with central opening, fitting said pan as a false bottom and said drain as an entrance, and having a multiplicity of upstanding lint engaging pins spaced apart slightly in a group around said opening, and a perforated cleaning plate removably lying 30 flat on the disc with spout depending through the opening and into the said drain; the pins on the disc fitting the plate perforations and upstanding thence in the path of the water as it flows to the said drain. 35

Signed at Boston, Massachusetts, this fifth day of October, 1926.

JOSEPH ARMSTRONG.
